YARN WINDING MACHINE

Alfred N. Altemus, Philadelphia, Pa.

Application November 11, 1929
Serial No. 406,265

15 Claims. (Cl. 242—29)

This invention relates to improvements in machines for winding yarn or thread upon conical or other cores or foundations and particularly to such machines wherein the yarn guide is raised and lowered to form open helical layers of yarn upon the cone or foundation, and wherein gain movements are imparted to the yarn guide during the raising and lowering thereof to build the layers of yarn upwardly upon one another and upon the cone or foundation for the formation of the desired yarn package.

The object of my invention is to provide a novel, simple and efficient machine, first, whereby the gain movements of the yarn guide may be automatically stopped upon the completion of a yarn package of a predetermined size and upon the breakage or discontinuance of the yarn being guided thereby; second, whereby the rotation of the winding spindle may be automatically stopped upon the stoppage of the gain movements of the yarn guide, upon the completion of a yarn package of a predetermined size, and upon the breakage or discontinuance of the yarn being guided by the yarn guide; and, third, whereby the yarn guide may be automatically operated and controlled during its up and down movements to cause it to follow a line approximating the inclination of the conical surface of the yarn package being wound or produced.

The invention consists of the elements and the combinations of them hereinafter described and claimed.

In the accompanying drawings, illustrating the invention,

Figure 1 is a front view, partly broken away, of a yarn winding machine embodying my invention.

Figure 2 is a transverse vertical section through the machine.

Figure 3 is a top view, partly broken away, showing the winding spindle, the yarn guide and part of the mechanism for operating the yarn guide.

Figure 4 is a sectional detail of the nut gear and adjuncts for imparting the gain movements of the yarn guide.

Figure 5 is a view partly broken away of part of the automatic stop mechanism showing the parts as seen from the side thereof opposite to the side shown in Fig. 2.

Figure 6 is a sectional detail showing part of the mechanism shown in Fig. 5, on line 6—6 of Fig. 5.

Figure 7 is a view of the part shown in Fig. 5 as seen from the right hand side of Fig. 5.

Referring to the drawings, the main frame of the machine includes the end standards 2 connected by the horizontal top bar 3.

A spindle 4 is mounted to rotate in upper and lower bearings 5 and 7 forming part of a bracket 6 which is secured to and projects from the frame bar 3. The spindle 4 is adapted to receive a cone 8 or other foundation upon which the thread or yarn is to be wound to constitute the yarn package.

The lower end portion of the spindle 4 is provided with a whirl disc 9 which rests normally on the leather covering 10 secured to the periphery of a driving wheel 11. The driving wheel 11 is carried by a horizontal shaft 12 which extends between and is journaled in bearings on the standards 2. The shaft 12 constitutes the main driving shaft of the machine and it is provided with a suitable sprocket wheel or gear 13 by means of which it may be driven by a suitable motor.

The machine is provided with a vertically reciprocal builder frame or support 14 comprising a horizontal rail 15 and vertically arranged, parallel shafts or rods 16 connected to and extending downwardly from the respective end portions of the rail 15. The shafts or rods 16 are slidably in bearings 17 on the end standards 2, and their lower end portions are provided with brackets 18 carrying rollers 19 which rest upon cams 20 on a horizontal shaft 21. The shaft 21 extends between and is journaled in bearings on the end standards 2 and it is driven by gearing 22 interposed between it and the driving shaft 12 as clearly shown in Fig. 1. The cams 20 are shaped as shown in Fig. 2 to effect the desired up and down movements of the builder frame 14 during the operation of the machine.

The rail or support 15 carries a builder screw 23 which rises fixedly therefrom. Fitted to turn slightly on the screw 23 and to slide longitudinally thereon is a sleeve 24 on which a nut gear 25 is rotatably mounted. The gear 25 has a plate or arm 26 engaged with the thread of the screw 23 to cause upward movement of the nut gear 25 and sleeve 24 when the gear is turned in the direction of the arrow in Fig. 3. One end of the plate 26 is pivoted, at 27, to the gear 25, and the other end of the plate 26 is held normally in engagement with the screw 23 by a spring 28 connecting the plate and gear 25. After moving the arm 26 from engagement with the screw 23 the nut gear 25 and sleeve 24 may be raised or lowered on the screw into any desired position thereon.

The sleeve 24 forms the fulcrum part of a yarn guiding arm or lever 29 having arms 30 and 31 projecting from the sleeve 24. The free end portion of the arm 30 has a bracket 32 adjustably secured thereto carrying a yarn guide 33 for directing yarn to the cone 8, carried by the spindle 4. This guide 33 may be of any approved form. As herein illustrated it comprises two parallel bars 34 secured to and projecting from the bracket 32 and forming a yarn passage 35 between them. The bracket 32 is provided with a round bar 36 which projects therefrom outwardly of and parallel to the bars 33, and the yarn 37 passes beneath the bar 36 before entering the yarn passage 35. This bar 36 may be formed of glass or other suitable wear resisting material.

The strand of thread or yarn 37 is drawn downwardly to and then beneath the bar 36 to and through the passage 35 from a suitable source of supply by the operation of winding it upon the cone 8.

Any suitable devices may be employed to support the yarn 37 at the source of supply thereof and guide it therefrom downwardly to the bar 36 and yarn guide 33, such, for example as the devices shown and described in Patent No. 1,676,374, dated July 10, 1928.

The operation of winding the yarn 37 upon the cone 8 draws the yarn guide 33 and lever arm 30 toward the cone 8, and the movement thereof in that direction is limited by the engagement of a bracket 38, secured on the arm 31 of the lever 29, with the surface 39 of a vertically extending cam 40. This cam 40 has a sleeve or collar 41 thereon which is slidably fitted to a flat, vertically arranged bar 42 the lower end of which is secured to a bracket 43 which is secured upon the frame bar 3. The collar 41 and therewith the cam 40 are vertically movable on the bar 42, and the collar 41 is provided with a flat friction spring 44 which bears against one side of the bar 42 to support the cam 40 in the different positions to which it is moved on the bar 42, as will be hereinafter explained.

The cam surface 39 is set at an incline with relation to the axis of rotation of the spindle 4 so that, during the raising and lowering of the frame 14, the pull of the yarn 37 against the yarn guiding bar 36 will hold the bracket 38 against the cam surface 39 and that such surface will move the lever 29 and therewith the yarn guiding bars 34 and 36 toward the spindle 4 during the upward movement of the frame 14 and away from the spindle during the downward movement of the frame 14 for a purpose hereinafter explained.

The length of the cam surface 39 is equal to or slightly greater than the extent of the up and down movements of the frame 14, and the cam 40 is provided with upper and lower projections 45 and 46 at the respective ends of the surface 39. After the lever 29 has been raised on the screw 23 by turning and thereby raising the nut gear 25 on the screw, the bracket 38 is adapted to engage the projection 45 and raise the cam 40 on the bar 42, to the extent that the lever 29 has been raised on the screw, during the upward movement of the frame 14, and when the nut gear 25 and therewith the lever 29 are lowered on the screw 23 the bracket 38 is adapted to engage the projection 46 and lower the cam 40 on the bar 42 for purposes hereinafter explained.

Extending parallel to the axis of the screw 23 is a shaft 47 which is adapted to turn and to slide vertically in a bearing formed by the bracket 43.

75 The upper end portion of the shaft 47 has an

elongated pinion 48 formed on or secured thereto which is in mesh with the nut gear 25. The teeth of the nut gear are adapted to slide through the spaces between the teeth of the pinion 48 when the nut gear is raised and lowered, and the 80 nut gear is in mesh with the pinion to be rotated thereby at all times. The lower end of the shaft 47 is provided with a bevel gear wheel 49 normally in mesh with a similar wheel 50 on a horizontal shaft 51 which extends parallel to the main driving shaft 12 and which turns in bearings on the main frame of the machine.

The shaft 51 is provided with a ratchet wheel 52 adapted to be turned by a pawl 53 pivoted, at 54, to a collar 55 which is secured upon one of the rods 16 of the builder frame 14. The pawl 53 moves into engagement with the ratchet wheel 52 by gravity and the pawl engages the ratchet wheel and turns it during each upward stroke of the builder frame 14.

The extent to which the pawl 53 moves the ratchet wheel 52 during each upward movement of the builder frame 14 is governed by a stop screw 56 which is vertically adjustable in a lug on the pawl carrying collar 55. The lower end 100 of the screw 56 is directly above an arm 57 on the pawl 53, and, during the upward movement of the builder frame, the screw 56 engages the arm 57 and moves the pawl 53 from operative engagement with the ratchet wheel 52 after the 105 pawl has moved the ratchet wheel a predetermined distance which is governed by the position of adjustment of the screw 56. Each time the builder frame 14 is moved upwardly during the reciprocation thereof, the ratchet wheel 52 turns the shaft 51, the gear wheels 49 and 50, the pinion 48 and the nut gear 25 to impart the gain movements to the yarn guide 33 carried by the nut gear.

The whirl disc 9 constitutes a driving element 115 for rotating the spindle 4 and the wheel 11 actuated by the main driving shaft 12 of the machine constitutes a driven element for actuating the driving element 9. The lower portion of the spindle 4 is provided with a square collar 58 which is secured thereto and which extends into a corresponding opening in the whirl disc 9 to cause the rotation of the spindle with the disc.

The disc 9 has an upward extending sleeve 59 formed thereon and having an annular groove 60 therein providing an annular flange 61 presently referred to. The disc 9 and sleeve 59 are slidably vertically on the spindle 4 and collar 58, and the engagement of the disc with the collar causes the spindle to be rotated with the disc 130 when it is rotated and permits the disc to be raised and lowered without raising and lowering the spindle.

At one side of the spindle bearing 5 is an arm 62 the lower end of which is pivoted, at 63, to the bearing 5, and the upper end of which is pivoted, at 64, to an arm or part 65 and also to the upper end of an arm or link 66. The arm or part 65 extends forwardly from the pivot 64 and has a handle 67 on the forward end thereof, and it also extends rearwardly from the pivot 64 and has a tooth 68 (Fig. 5) formed thereon which bears against the side of the lower end of a vertical pin 69 which is fitted to slide in a bearing formed on the bracket 43. The 145 upper end of the pin is directly beneath a collar 70 which is secured on the shaft 47 at the base of the pinion 48, whereby, when the pin 69 is raised, the shaft 47 will be raised to disengage the bevel gear wheel 49 from the bevel gear 150

wheel 50 and thereby stop the rotation of the pinion 48 by the gear wheel 50.

The arm or part 65 is drawn rearwardly and its rearward end portion is drawn upwardly by 5 the action of a spring 71 the forward end of which is connected to the part 65 and the rearward end of which is connected to a pin 72 which projects from the bracket 43 above the point of connection of the spring with the part 10 65. Thus the spring 71 holds the part 65 normally in the position shown by full lines in the drawings with its tooth 68 in engagement with the pin 69. When the rearward end of the arm 65 is depressed against the action of 15 the spring 71, the tooth 68 of the arm 65 is disengaged from the lower end of the pin 69, thereby releasing the arm 65 and permitting the spring 71 to move it rearwardly to the position shown by dot-and-dash lines in Fig. 5. The 20 forward and rearward movements of the arm 65 are limited by the end walls of a slot 73 therein engaging the pin 72 which extends through the slot. The top wall of this slot 73 also limits the upward and downward movements of the 25 rearward end of the arm 65.

The arm 65 is provided with a cam surface 74 which is inclined upwardly and forwardly from the top of the tooth 68. When the arm 65 is released from the pin 69 and is moved rearwardly by the spring 71 to the dot-and-dash line position shown in Fig. 5, the cam surface 74, acting against the bottom of the pin 69, raises the pin and thereby raises the gear wheel 49 from engagement with the gear wheel 50 and 30 stops the rotation of the pinion 48; and, when the arm 65 is moved forwardly by hand to the normal position thereof, the cam 74 permits the pin 69 and shaft 47 to be lowered by gravity until the bevel gear wheel 49 is re-engaged with 35 the bevel gear wheel 50 causing the re-actuation of the pinion 48 and nut gear 25 by the gear wheel 50, whereupon the spring 71 re-engages the tooth 68 with the pin 69 when the arm 65 is released in its normal or set position. 40

45 The lower end of the arm or link 66 extends to a position adjacent to one side of the sleeve 59 of the whirl disc 9 and it has a pin 75 secured to its lower end portion. The pin 75 extends from the link 66 inwardly through and 50 beyond a vertical slot in a fixed arm 76 which is formed on and extends downwardly from the bearing 5. When the part 65 is released and moved rearwardly from its normal position shown in Fig. 2 to the position shown by dot-and-dash lines in Fig. 5, and then returned to its normal 55 position, the link 66 and its pin 75 will be raised and lowered by the action of the arm 62.

The inner end portion of the pin 75 extends into the groove 60 (Fig. 1) in the sleeve 59 of the whirl disc 9 and it is adapted to engage the flange 61 and raise and lower the disc 9 from and into engagement with the leather covering on the wheel 11, thereby disconnecting the disc or spindle driving element 9 from the wheel 60 or driven element 11 and stopping the actuation of the disc 9 and spindle 4 by the wheel 11 when the disc is raised; and connecting the disc 65 and wheel 11 and resuming the actuation of the disc 9 and spindle 4 by the wheel 11 when the disc is lowered.

It will now be understood that when the arm or part 65 is set in its normal position shown in Fig. 2, the nut gear 25 and the winding spindle 4 will be actuated by the mechanism of the machine, and that when the arm 65 is re-

leased and moved rearwardly by the spring 71 it will stop the actuation of the nut gear 25 and the winding spindle 4 while the actuating wheels 50 and 11 therefor, respectively, continue their operation under the influence of the main driving shaft 12 of the machine.

The rearward end portion of the arm 65 (Fig. 5) has a substantially horizontal surface 77 which extends rearwardly from the tooth 68. Located directly over this surface is the free end portion of a horizontally extending portion 78 on the lower arm of a lever 79 which is fulcrumed, at 80, on the bearing bracket 43, and which has a straight arm 81 which extends upwardly from the fulcrum 80. This lever 79 is movable on its fulcrum 80 within the limits allowed by a pin 82 which projects from the bearing bracket 43 and into an opening 83 in the lever arm 78.

When the lever 79 is moved in the direction of the arrow in Fig. 7 the lever arm 78 will depress the rearward end of the arm 65 and disengage the tooth 68 from the pin 69 and thereby release the arm 65 for its actuation by the spring 71 to stop the actuation of the nut gear 25 and winding spindle 4 as previously described; and when the arm 65 is restored to its normal position, as shown in Fig. 2, by hand, as previously explained, the rearward end of the arm 65 will move the lever 79 back to its normal position shown in Figs. 1 and 7.

The lever arm 81 is located adjacent to the cam 40 and it is provided with a collar 84 which is vertically adjustable thereon. The collar 84 is provided with a suitable set screw to hold it in positions of adjustment, and it is also provided with a downwardly extending projection 85 for a purpose presently appearing.

The cam 40 has a projecting arm 86 formed thereon, and fulcrumed, at 87, on the arm 86 is a small lever 88, one arm 89 of which is bent and extends to a position beneath the projection 85 on the collar 84. The relation of the lever arm 89 to the lever arm 81 is such that when the cam 40 is raised on the bar 42 a sufficient distance the lever arm 89 will engage the projection 85 and will be thereby forced downwardly on its fulcrum 87 and thus caused to engage the lever arm 81 and move it in the direction of the arrow in Fig. 7 for the release of the arm 65 and the consequent stoppage of 120 the actuation of the winding spindle 4 and the nut gear 25, as previously described.

The arm 31 of the yarn guiding lever 29 carried by the nut gear 25 is provided with a projection 90 which passes the small lever 88 each time the lever is raised and lowered by the builder frame 14, and which is moved to and from a position directly beneath the lever 88 as the bracket 38 on the lever 29 moves down and up in contact with the cam surface 37 against which the bracket is held 130 by the pull of the yarn 37 passing to the cone 8.

When the yarn guiding lever 29 is in its lowermost position with relation to the cam 40 the projection 90 is directly beneath the lever 88, and, so long as the yarn 37 is feeding to the cone 8 the 140 bracket 38 will follow the cam surface 39 and the projection 90 will be moved from beneath the lever 88 to clear the same as the lever 29 and bracket 38 ascend. When, however, the yarn 37 breaks or discontinues its feed to the cone 8 for 145 any reason, the pull of the yarn will no longer maintain the bracket 38 in engagement with the cam surface 39, after the cam surface 39 has moved the projection 90 to a position beneath the lever 88 on the next descent of the lever 88 and 150

the projection 90 will remain in such position. Therefore, upon the next upward movement of the lever 29 the projection 90 thereon will engage the lever 88 and thereby rock the same on its fulcrum 87 and cause its arm 89 to engage the lever arm 81 and move it in the direction of the arrow in Fig. 7 for the release of the arm 65 and the consequent stoppage of the actuation of the winding spindle 4 and the nut gear 25.

If the inclination of the cam surface 39 is insufficient to cause the projection 90 to move to a position beneath the lever 88 during the downward movement of the projection 90 while the pull of the yarn 37 holds the bracket 38 against the cam surface 39, the action of the pinion 48 against the nut gear 25 will cause the friction between the nut gear and the sleeve 24 of the lever arm 31 to move the projection 90 to the desired position beneath the lever 88 for the stoppage of the actuation of the winding spindle 4 and nut gear 25 upon the next upward movement of the projection 90 when the yarn 37 breaks or is discontinued and thereby ceases to press the bracket 38 against the cam surface 39.

The drawings show the positions of the parts of the machine which they occupy just prior to the completion of the winding of the yarn package 91 on the spindle 4. The package 91 comprises the foundation or cone 8 and the body of yarn 92 wound thereon. Prior to the beginning of the winding of the body of yarn 92 upon the cone 8, the nut gear 25 is lowered by hand upon the screw 23 to a position where the yarn guide 33 will start the winding of the yarn at the level 93 on the cone 8; and at the same time the cam 40 is lowered on the bar 42 by the lowering of the nut gear 25. When these parts are lowered the pinion 48 and winding spindle 4 are idle and the part 65 is out of its normal position shown in Fig. 2.

Assuming that the nut gear 25 and cam 40 have been lowered to the positions above set forth and that the main driving shaft 12 is being continuously rotated, the operation of the machine, briefly described, is as follows:

The yarn 37 is attached to the lower portion of the cone 8, in the usual manner, and the part 65 is moved forwardly by hand to the normal position shown in Fig. 2, thereby starting the actuation of the pinion 48 and the winding spindle 4.

As the spindle 4 and cone 8 thereon rotate, the yarn 37 passes through the yarn guide 33 and is wound upon the spindle, and, during the winding operation, the builder frame 14 and therewith the screw 23, nut gear 25 and yarn guide 33 are raised and lowered by the cams 20 for building successive, open, helical layers of yarn upon the cone 8 and upon each other.

The extent of the up and down movements of the yarn guide 33 by the builder frame 14 is equal to the distance between the lines 95 and 96 Fig. 2.

At the beginning of the winding of the body of yarn 92 upon the cone 8, the yarn guide 33 is moved up and down to feed yarn to the cone 8 between the levels 93 and 94, and while the up and down traverse of the guide 33 under the influence of the builder frame 14 is substantially constant, the yarn guide 33 is periodically raised on the screw 23 with respect to the builder frame 14 to impart gain movements to the guide so that the successive helical layers of yarn will be placed upon the cone 8 at successively increasing higher levels until at the completion of the winding of the body of yarn 92, the final layer of yarn extends between the levels 95 and 96 or substantially so.

These gain movements are imparted to the yarn guide 33 by the pawl 53 turning the ratchet wheel 52 and causing it to turn the bevel gear wheels 49 and 50 and pinion 48 which turns the nut gear 25 and causes it and the yarn guide 33 to move upwardly on the screw 23 a slight distance at each upward movement of the builder frame 14 during the reciprocation thereof.

During the traverse or up and down movements of the yarn guide 33 the pull of the yarn 37 upon the guide 33 holds the bracket 38 against the cam 40 and the cam 40 moves the guide 33 gradually away from the cone 8 during the downward movement of the guide and permits the pull of the yarn to move the guide gradually toward the cone during the upward movement of the guide so that, during the up and down traverse of the guide, it will follow a line substantially parallel to or approximating the adjacent surface of the body of yarn being wound upon the cone. This movement of the yarn guide 33 keeps it at all times in close proximity to the body of yarn 92 upon the cone and causes the helical layers of yarn to be laid on the cone 8 in a manner to extend up and down thereon a distance more nearly approximating the full traverse of the yarn guide 33 than in machine constructions wherein the yarn guide is moved up and down in a vertical line; because, in the latter case, the yarn guide is distinctly farther from the cone at the top of its stroke than at the bottom thereof.

Each time a gain movement is imparted to the yarn guide 33 the bracket 38 on the lever 29 carrying the guide 33 engages the projection 45 on the cam 40 and moves the cam upwardly on the bar 42 a distance equal to the extent of the gain movement of the guide.

Upon the completion of the winding of the body of yarn 92 upon the cone 8, the upward movement of the cam 40 causes the arm 89 of the lever 88 carried by the cam 40 to engage the projection 85 of the collar 84 on the lever arm 81 and operate the lever 79 to release the part 65 and thereby stop the operation of the winding spindle 4 and pinion 48, and thus stop the winding of the yarn 92 upon the cone 8 and also stop the gain movements of the yarn guide 33 while the main shaft 12 continues to rotate and the builder frame 14 continues to move up and down.

The size of the yarn package 91 or the body of yarn 92 wound upon the cone 8 may be governed and controlled by adjusting the collar 84 up and down upon the lever arm 81. When the collar 84 is moved to a lower position on the lever arm 81, the winding operation will be automatically stopped when the yarn guide reaches a lower level; and, when the collar 84 is moved to a higher position on the lever arm 81 the winding operation will be automatically stopped when the yarn guide reaches a higher level.

After the completion of the winding of the body of yarn 92 upon the cone 8 and the tripping of the part 65 to stop the rotation of the spindle 4 and the operation of the pinion 48, the yarn 37 is severed and the yarn package 91 or the cone 8 containing the body of yarn 92 is removed from the spindle 4 and a fresh, empty cone is placed upon the spindle for a succeeding yarn winding operation. This being done, the arm 26 on the nut gear 25 is moved out of engagement with the screw 23 and the nut gear 25 and therewith the yarn guide 33 is lowered on the screw 23 until the guide 33 is in a position to deliver yarn to the fresh cone placed upon the spindle, at the level 93 when the builder frame 14 is in the down position.

tion, the arm 26 of the nut gear 25 is re-engaged with the screw 23, the yarn 37 being delivered by the guide 33 is attached to the fresh cone, the arm or part 65 is moved forward to its set position 5 to start the operation of the winding spindle 4 and pinion 48 and the winding operation is repeated.

If, at any time during the winding of the body of yarn 92 upon the cone 8, the strand of yarn 10 37 should break or be discontinued for any cause, the cam 40 will move the projection 90 on the lever 29 to a position beneath the lever 88 during the next downward movement of the builder frame 14 and the projection 90 will remain in a position beneath the lever 88 during the succeeding upward movement of the builder frame because there will be no yarn pull to hold the bracket 38 15 against the cam 40; consequently, during such next succeeding upward movement of the builder frame 14 the projection 90 will engage the lever 88 and cause it to operate the lever 79 to trip the arm or part 65 and thus stop the rotation of the winding spindle 4 and also stop the operation of the pinion 48 for effecting the gain movements 20 of the yarn guide.

If it should be desired for any reason whatsoever to stop the rotation of the winding spindle 4 and the operation of the pinion 48 at any time during the winding operation, the same may be 25 easily and quickly done by merely raising the forward end of the part or arm 65 and thereby tripping it by releasing its tooth 68 from the pin 69, or the part or arm 65 may be easily and quickly tripped by moving the level arm 81 in the direction of the arrow in Fig. 7 by hand.

The frame bar 15 may be provided with any desired number of the brackets 8 and 43 supporting additional winding spindles and shafts like the winding spindle 4 and shaft 47, and such 40 additional winding spindles and shafts may be actuated by the main driving shaft 12 and the shaft 51, respectively, like the spindle 4 and the shaft 47 are actuated thereby for the same purpose.

45 I claim as my invention:

1. In a yarn winding machine, the combination of a supporting frame, a winding spindle rotatably supported by the frame, a driving wheel, a whirl disc carried by the spindle and adapted 50 to rotate the same and movable into and out of engagement with the driving wheel, yarn guiding means for directing yarn toward the spindle, and means controlled by a yarn guided by said means to move said disc out of engagement with said 55 wheel upon the breaking of a yarn guided by said means.

2. In a yarn winding machine, the combination of a supporting frame, a winding spindle, a driving element for rotating the spindle, a driven element for rotating the driving element, vertically 60 movable support, means to reciprocate the support a yarn guiding device carried by the support movable toward and from the spindle and adapted to be moved toward the spindle by a yarn 65 guided thereby, means to move the device away from the spindle, and means operated by said support and controlled by the breaking of a yarn guided by the device to stop the operation of the driving element by the driven element after the 70 device has been moved by said means away from the spindle.

3. In a yarn winding machine, the combination of a supporting frame, a winding spindle rotatably supported by the frame, a driving wheel, a 75 whirl disc carried by the spindle and adapted to

rotate the same and movable into and out of engagement with the driving wheel, yarn guiding means for directing yarn toward the spindle, a part movable from either one to the other of two positions, means controlled by a yarn guided by said means to move said part to one of said positions, means to move said part to the other of said positions, and means operated by said part when in the last named position to move said disc out of engagement with said wheel following the breaking of a yarn guided by said means.

4. In a yarn winding machine, the combination of a supporting frame, a winding spindle, a driving element for rotating the spindle, a driven element for rotating the driving element, a vertically movable support, means to reciprocate the support, yarn guiding means carried by the support for directing yarn toward the spindle, and means operated by the support and controlled by a yarn guided by said guiding means to stop the operation of the driving element by the driven element upon the breaking of said yarn.

5. In a yarn winding machine, the combination of a supporting frame, a winding spindle, a driving element for rotating the spindle, a driven element for rotating the driving element, a vertically movable support, means to reciprocate the support, yarn guiding means for directing yarn toward the spindle, a part carried by the support and movable from either one to the other of two positions relative to the support, means controlled by a yarn guided by said means to move said part to one of said positions, means to move said part to the other of said positions, and means operated by said part when in the last named position to stop the operation of the driving element by the driven element following the breaking of a yarn guided by said means.

6. In a yarn winding machine, the combination of a supporting frame, a winding spindle, a driving element for rotating the spindle, a driven element for rotating the driving element, a vertically movable support, means to reciprocate the support a yarn guide carried by the support for directing yarn toward the spindle, a part manually movable to an operative position and, automatically movable therefrom to an inoperative position when released, means to releasably hold said part in its operative position, means operated by said part when moved to its inoperative position to stop the operation of the driving element by the driven element, and means operated by said support and controlled by a yarn guided by said guide for releasing said part upon the breaking of said yarn.

7. In a yarn winding machine, the combination of a supporting frame, a winding spindle, a driving element for rotating the spindle, a driven element for rotating the driving element, a vertically movable support, means to reciprocate the support a yarn guide carried by the support for directing yarn toward the spindle, a part manually movable to an operative position and automatically movable therefrom to an inoperative position when released, means to releasably hold said part in its operative position, means operated by said part when moved to its inoperative position to stop the operation of the driving element and operated by said part when moved to its operative position to start the operation of the driving element by the driven element, and means operated by said support and controlled by a yarn guided by said guide for releasing said part upon the breaking of said yarn.

8. In a yarn winding machine, the combination

- of a supporting frame, a winding spindle, a driving element for rotating the spindle, a driven element for rotating the driving element, a vertically movable builder, means to reciprocate the builder, a yarn guide carried by the builder, mechanism for periodically raising the yarn guide to progressively higher levels with relation to the builder, actuating means for said mechanism, a movable member having an abutment, means carried by the yarn guide for engaging said abutment and thereby moving said member when the yarn guide reaches a predetermined level, means operated by said member to automatically stop the operation of said driving element by said driven element, and means operated by said member to automatically stop the operation of said mechanism by said actuating means.
9. In a yarn winding machine, the combination of a supporting frame, a winding spindle, means for rotating the spindle, a vertically movable builder, means to reciprocate the builder, a yarn guide carried by the builder, a vertically movable shaft, means operated by said shaft for periodically raising the yarn guide to progressively higher levels with relation to the builder, a gear wheel, means for periodically actuating the gear wheel, a gear wheel on said shaft normally in mesh with the first named gear wheel and adapted to be moved out of mesh therewith when said shaft is raised, a movable member having an abutment, means carried by the yarn guide for engaging said abutment and thereby moving said member when the yarn guide reaches a predetermined level, and means operated by said member to raise said shaft.
10. In a yarn winding machine, the combination of a supporting frame, a winding spindle, means for rotating the spindle, a vertically movable builder, means to reciprocate the builder, a yarn guide carried by the builder, mechanism for periodically raising the yarn guide to progressively higher levels with relation to the builder, actuating means for said mechanism, a part manually movable to an operative position and automatically movable therefrom to an inoperative position when released, means to releasably hold said part in its operative position, a cam operated by said part, means operated by said cam when said part is moved to its inoperative position to automatically stop the operation of said mechanism by said actuating means, a member movable independently of said part and having an abutment, means carried by the yarn guide for engaging said abutment and thereby moving said member when the yarn guide reaches a predetermined level, and means operated by said member for releasing said part.
11. In a yarn winding machine, the combination of a supporting frame, a winding spindle, a driving element for rotating the spindle, a driven element for rotating the driving element, a vertically movable builder, means to reciprocate the builder, a yarn guide carried by the builder, mechanism for periodically raising the yarn guide to progressively higher levels with relation to the builder, actuating means for said mechanism, a part manually movable to an operative position and automatically movable therefrom to an inoperative position when released, means to releasably hold said part in its operative position, means operated by said part when moved to its inoperative position to stop the operation of the driving

element by the driven element, a cam operated by said part, means operated by said cam when said part is moved to its inoperative position to automatically stop the operation of said mechanism by said actuating means, a movable member having an abutment, means carried by the yarn guide for engaging said abutment and thereby moving said member when the yarn guide reaches a predetermined level, and means operated by said member for releasing said part.

12. In a yarn winding machine, the combination of a supporting frame, a vertically arranged spindle, means for rotating the spindle, a vertically movable support, means for reciprocating the support and for raising it to progressively higher levels independently of its reciprocative strokes, a yarn guide carried by the support and movable thereon toward and from the spindle for delivering yarn thereto, a vertically movable cam engaged by the guide and constructed to move it gradually away from the spindle during the movement of the support in one direction at each reciprocative stroke thereof, and means for raising the cam to progressively higher levels in accordance with the movements of the support to progressively higher levels.

13. In a yarn winding machine, the combination of a supporting frame, a vertically arranged spindle, means for rotating the spindle, a vertically movable support, means for reciprocating the support and for raising it to progressively higher levels independently of its reciprocative strokes, a yarn guide carried by the support and movable thereon toward and from the spindle for delivering yarn thereto, and a vertically movable cam engaged by the guide and constructed to move it gradually away from the spindle during the movement of the support in one direction at each reciprocative stroke thereof, said cam having an abutment and said guide having a part adapted to engage said abutment and raise the cam to progressively higher levels in accordance with the movements of the support to progressively higher levels.

14. In a yarn winding machine, the combination of a supporting frame, a winding spindle, means to rotate the spindle, a builder screw, a sleeve fitted to slide longitudinally on the screw in guiding contact therewith, means to prevent the sleeve from rotating on the screw, a yarn guide carried by the sleeve, a nut gear rotatably mounted on the sleeve, means connected to the nut gear and engaging the thread of the builder screw to cause the gear and sleeve to move longitudinally on the screw when the gear is rotated, and means to rotate the nut gear.

15. In a yarn winding machine, the combination of a supporting frame, a winding spindle, means to rotate the spindle, a vertically extending builder screw, a sleeve fitted to slide longitudinally on the screw in guiding contact therewith, means to prevent the sleeve from rotating on the screw, a yarn guide carried by the sleeve, a nut gear rotatably mounted on the sleeve, means connected to the nut gear and engaging the thread of the builder screw to cause the gear and sleeve to move longitudinally on the screw when the gear is rotated, a vertically extending elongated pinion in mesh with the nut gear, and means to rotate the pinion.

ALFRED N. ALTEMUS.
